VOICE-TRANSMITTING GAS MASK

Armand V. Motsinger, near Aberdeen, Md.

Application May 17, 1938, Serial No. 208,408

12 Claims. (Cl. 128—141)

(Granted under the act of March 3, 1883, as
amended April 30, 1928; 370 O. G. 757)

1

The invention described herein may be manufactured and used by and for the Government for governmental purposes, without the payment to me of any royalty thereon.

This invention relates to voice-transmitting gas masks and has for an object to provide a gas mask through which a person can talk without the use of electrical or other outside energy.

Another object of this invention is to provide a diaphragm which will readily transmit the human voice.

Another object of this invention is to provide a sound box or acoustical chamber next to a diaphragm in order to increase the transmission of speech through the diaphragm.

Another object of this invention is to provide a sound box or acoustical chamber that is adjustable so as to conform to the individual voice of the wearer of a mask or to the sound characteristics of a given mask.

Another object of this invention is to provide a facepiece of a gas mask with diaphragms and acoustical chambers on either side of the facepiece which may respond to different sound frequencies.

With the foregoing and other objects in view, the invention consists in certain novel features of construction and arrangement of parts as will be more fully disclosed in connection with the accompanying drawings.

In the drawings:

Fig. 1 is a sectional view on line 1—1 of Fig. 2 of a facepiece of a gas mask in place on the face, showing the position of the acoustical chamber and diaphragm.

Fig. 2 is a front view of a facepiece, in place on a man's head, showing the diaphragm in the front part of the facepiece.

Fig. 3 is a front view of a facepiece, in place on a man's head, showing angletubes with diaphragms on the side of the facepiece.

Fig. 4 is a front view of an angletube of a facepiece showing deflectors in the acoustical chamber and position of the diaphragm.

Fig. 5 is a section on line 5—5 of Fig. 4 showing a diaphragm and acoustical chamber with sound deflectors.

Fig. 6 is another variation of angletube having an acoustical chamber. It shows the acoustical chamber with holes around the edge for entrance of sound.

Fig. 7 is a sectional view on line 7—7 in Fig. 6.

Fig. 8 is a front elevation of an angletube showing an adjusting device for changing the sound characteristics of the acoustical chamber.

2

Fig. 9 is a cross section on line 9—9 of Fig. 8 showing an acoustical chamber which can be varied in shape and size to respond to various voice characteristics.

5 Fig. 10 is a rear elevation of the angletube with adjustable chamber shown in Figs. 8 and 9.

Corresponding and like parts are referred to in all the views by like reference characters.

A diaphragm when transmitting speech does 10 not resonate at one frequency but must vibrate in the range of frequencies corresponding to the voice range. The kinetic energy must be overcome at each cycle and since the power available in the voice is low, the kinetic energy of the diaphragm must be low. Therefore the diaphragm 15 must be as light in weight as possible. For use in gas masks the diaphragm must be mechanically strong and of a material to prevent the passage of gases.

20 In accordance with this invention the diaphragm is formed of a plurality of separate plies of material secured together only at their peripheries. Diaphragms made of cellulose derivative such as "Cellophane," cellulose nitrate, or

25 cellulose acetate, have been successfully used, with two to five plies. Preferably four plies of cellulose acetate are used, each ply about one thousandth of an inch thick, as this assembly affords mechanical strength, impermeability to 30 gases, resistance to deterioration, and vibration range to accommodate the human voice. A sufficient number of plies must be used to prevent chatter.

Voice diaphragms of individual plies secured 35 only at their edges have a very small energy loss since the separate plies may vibrate individually. A diaphragm made in this way has no undesirable resonance since the separate lamina dampen the adjacent lamina.

40 Gas mask facepieces are usually formed of flexible material to conform closely to the wearer's face. In order to avoid a plurality of connections to the facepiece, it is common practice to provide one rigid member formed of metal, which is connected to the facepiece and by which the air enters

45 and leaves the facepiece. This member, which also serves to hold the facepiece in shape and prevents collapsing due to inhalation, is known in the trade as an angle tube and is so designated 50 herein.

Referring to the drawings, the plied diaphragms 11 formed of a plurality of plies of cellulose derivative is secured at its periphery against a gasket 12. From Figure 1 it will be noted that 55 an angle tube 14 is suitably secured in a gas-tight

manner to the flexible facepiece 15, has an undercut annular flange 16 against which gasket 12 is pressed. Diaphragm 11 and gasket 12 are secured in place by a crimped rim 17 of the metal acoustical box 18. Acoustical box 18 is a cup-shaped member with its rim progressively decreasing in depth from the upper to the lower portion, as seen in Figure 1. The bottom of box 18 has a plurality of openings 19 arranged adjacent the upper portion and in front of the wearer's mouth.

The gasket 12 engages against a beveled surface on flange 16, the arrangement being such that as the rim 17 is crimped in place and as pressure is applied to diaphragm 11 the gasket 12 is displaced outwardly to thus evenly stretch the diaphragm. Since there is not twisting action in stretching the diaphragm, there is no tendency to wrinkle or break the thin diaphragm.

A rubber outlet valve 21 may be secured to an outlet nipple 22 on the angle tube 14, and an inlet hose to inlet nipple 38. It has been found that the size and shape of the acoustical chamber formed by a box 18 affects the sound transmitted through the diaphragm, and the shape and size of the chamber varies for different voices. For average voices, the back or bottom of chamber 18 should be placed at an angle of 15° to the diaphragm 11.

Voice transmission may be further improved by baffles within the acoustical chamber. As seen in Figs. 1, 4 and 5, a baffle 23 having a curved upper edge to engage the acoustical box extends downwardly at an angle of about 42° to the base or back 18 of the box. Two side baffles 24 of substantially triangular shape extend from baffle 23 downwardly at about 65° to baffle 23. Baffles 23 and 24 just clear diaphragm 11 to allow free vibration thereof.

The openings 19 and baffles 23 and 24 concentrate the voice sound waves to the center of the diaphragm, thus increasing the efficiency of sound transmission.

In Figs. 6 and 7 is shown another shape of acoustical chamber. In this form the back 25 of the acoustical chamber is in the shape of a cone, with the inner point out of engagement with diaphragm 11. The side of the cone makes an angle of about 15° to the diaphragm. Sound enters the chamber through openings 26 in the cone. This chamber is also crimped to the angle tube to secure the diaphragm in place, as previously described, the acoustical chamber being on the inside of the facepiece.

Since the type of voice and the interior cavity of the facepiece affect the sound transmitted by a diaphragm when used with an acoustical chamber, it is sometimes desirable to make the acoustical chamber adjustable to accommodate it to different voices, as seen in Figs. 8, 9 and 10. In this form, the chamber has a resilient back 27 suitably secured to a metal cup 28 which in turn secures the diaphragm 11 to the angle tube. By moving the back 27 in or out, the size and shape of the acoustical chamber may be varied to suit the voice of the wearer. In the open extended position of the back, the acoustical chamber will best fit a tenor voice, whereas in the depressed position the chamber will best fit a bass voice. Resilient back 27 has a series of holes 29 around its periphery through which sound enters the chamber.

The resilient back 27 may be adjusted by a thumb screw 31 threaded to a strap 32 on the angle tube, the inner end of the thumb screw arranged to press the flexible facepiece material 15

against a bell crank 33. Crank 33 is pivoted at 34 to the angle tube, and its inner end engages the resilient back 27. Thumb screw 31 may have a numbered dial for cooperation with a mark 35 on the strap 32.

Two angle tubes with diaphragms and acoustical chambers may be mounted in the cheek portions of the facepiece as seen in Fig. 3. One angle tube 36 may have its acoustical chamber arranged to respond more efficiently to a tenor voice, the other angle tube 37 to a bass voice, thus giving a wider range of voice transmission without resorting to an adjustable acoustical chamber. The optimum size and shape of the chambers for a certain shape of facepiece may be determined by talking tests or by impressing known sound waves within the facepiece at various frequencies and measuring the sound transmitted through the diaphragms.

It will be understood that the invention is not limited to the precise details herein shown and described by way of illustration, since many changes and variations may be made therein by those skilled in the art without departing from the spirit of the invention nor exceeding the scope of the appended claims.

I claim:

1. A voice transmitting gas mask comprising a facepiece, and a diaphragm therein in voice transmitting relation to the mouth of the wearer, said diaphragm formed of a plurality of layers of thin gas-resistant material secured together only at their edges and stretched taut.

2. The invention as defined in claim 1 wherein said diaphragm is formed of a plurality of layers of a cellulose derivative.

3. The invention as defined in claim 1 wherein said diaphragm is formed of a plurality of layers of cellulose acetate.

4. In a voice transmitting mask, a sound box having a perforated bottom, an angle tube, a diaphragm formed of a plurality of plies of cellulose derivative positioned between said sound box and angle tube, and means to secure said sound box and angle tube together and simultaneously stretch said diaphragm, said plurality of plies being secured only at their edges.

5. A voice transmitting gas mask comprising a facepiece, an annular cup-shaped angle tube secured therein, a voice-transmitting diaphragm closing said angle tube, said diaphragm being formed of a plurality of separate layers of material secured together only at their edges, said angle tube having an annular lip having a diaphragm engaging surface at an angle to the plane of the diaphragm, said diaphragm being pressed against said surface to thereby stretch the diaphragm.

6. The invention as defined in claim 5 wherein a sound box is secured to said angle tube within the facepiece to concentrate sound waves on the diaphragm.

7. A voice transmitting gas mask comprising a facepiece, an angle tube secured therein, a diaphragm formed of a plurality of plies of gas-impermeable material, means to secure said diaphragm across said angle tube, said means securing said diaphragm only around its edge, and a sound amplifying box on the inside of said facepiece forming a chamber having a perforated bottom, said bottom being positioned at an angle to the diaphragm.

8. The invention as defined in claim 7 wherein said amplifying box has baffles therein sloping 75 toward the center of the diaphragm whereby

voice waves are concentrated toward said center. 9. The invention as defined in claim 7, wherein cooperating means are provided on the angle tube and amplifying box to secure these members together, said cooperating means also securing and stretching said diaphragm.

10. The invention as defined in claim 7, wherein said diaphragm is formed of three to five plies of cellulose acetate.

11. A voice transmitting gas mask comprising a facepiece, an angle tube secured therein, a diaphragm formed of a plurality of plies of gas-impermeable material, means to secure said diaphragm only around its edge, and a sound amplifying box on the inside of said facepiece, said box having closed side walls and a perforated bottom, said bottom being readily adjustable toward and from the diaphragm to thereby adjust the size of the sound box to the voice.

12. A voice-transmitting assembly for gas masks, comprising in combination, an angle tube, a sound amplifying box joined to the angle tube at one side of the latter, coacting means on the angle tube and on the sound amplifying box providing a joint therebetween, a diaphragm secured within the confines of said joint with the marginal edge only of said diaphragm being clamped between the coacting means on the angle tube and sound amplifying box, and said sound amplifying box having a wall adapted to be flexed toward and away from said diaphragm, and means accessible at the side of the angle tube opposite the sound amplifying box for adjustably flexing said wall.
